(57) **CLAIM**

I claim the ornamental design for a digital health monitor, as shown and described.

DESCRIPTION

FIG. 1 is a front, first side and bottom perspective view of a digital health monitor showing the my new design;

FIG. 2 -is a rear, second side and bottom perspective view thereof;

FIG. 3 is a rear elevational view thereof;

FIG. 4 is a front elevational view thereof;

FIG. 5 is a first side elevational view thereof;

FIG. 6 is a second side elevational view thereof;

FIG. 7 is a top plan view thereof;

FIG. 8 is a bottom plan view thereof;

FIG. 9 is a front, side and bottom perspective view of a second embodiment of digital health monitor showing my new design; and,

FIG. 10 is a front elevational view thereof.

The broken lines depict portions of the digital health monitor that form no part of the claimed design.
